SHARPENER

William J. Duncan, Houston, Tex.

Application January 3, 1941, Serial No. 372,965

5 Claims. (Cl. 51—214)

The invention relates to a sharpener for instruments such as knives, blades, etc.

It is one of the objects of the invention to provide a sharpener wherein the instrument is stroked transversely of the sharpening element with a longitudinal swinging motion so that the sharpening action will be the same as that obtained by using a steel.

Another object of the invention is to accurately position the instrument being sharpened as to angularity with respect to the sharpening element so that a uniform cutting edge will be provided.

Another object of the invention is to provide a carriage to slide with the instrument in the sharpening stroke so that the instrument may be received by the carriage and guided uniformly along the sharpening element.

Another object of the invention is to provide a horizontally disposed sharpening element with a guide carriage relative thereto.

Another object of the invention is to resiliently support a guide carriage for the instrument to be sharpened upon a sharpening device.

Still another object of the invention is to provide a carriage which has an adjustable portion thereon to accurately position an instrument to be sharpened by movement of the carriage.

A still further object of the invention is to provide a sharpening device with a spring pressed carriage so as to hold the carriage in proper position during the sharpening operation.

Other and further objects of the invention will be readily apparent when the following description is considered in connection with the accompanying drawings wherein:

Fig. 1 is a side elevation of one form of the sharpener with the carriage in place adjacent the sharpening element.

Fig. 2 is a top plan view looking down on the device of Fig. 1.

Fig. 3 is a transverse section taken on the line 3—3 of Fig. 1.

Fig. 4 is a perspective view of one form of the guide carriage.

Fig. 5 is a side elevation of a slightly modified form of the device wherein the carriage is mounted upon ball bearings.

Fig. 6 is a top plan view looking down on the device of Fig. 5.

Fig. 7 is a section taken on the line 7—7 of Fig. 5.

Fig. 8 shows another modification of the carriage support.

In Fig. 1 a base 2 is provided with the uprights

3 and 4 which serve as a support for the frame 5. This frame is in turn arranged to receive a sharpening element 7, such as a whetstone or hone. This element is preferably held in place by the upstanding clips 8 which may be struck out of the material in the bottom of the frame 5, as seen in Fig. 2.

It is to be understood that the sharpening element 7 may be of any desired length or width depending upon the type of sharpener which is contemplated. In order to hold the sharpener in proper position, a handle 10 is shown as affixed by the bolt 11 to the frame 5 and upright 3.

A carriage 15 has been illustrated as being slidably mounted in a position to enclose the hone or sharpening element 7, and this carriage is in the general configuration of a U-shaped body 16 having upstanding side plates 17 thereon.

These side plates fit around the frame 5 and the sharpening element 7, as seen in Figs. 1 to 3 inclusive. This carriage is arranged for sliding movement longitudinally of the sharpening element, and it is desired that the carriage be readily slideable along the sharpening element. With this in mind, a spring 18 has been positioned beneath the frame 5 and has the curved or bowed end 19 passed through the opening 20 into the bottom of the frame 5. The inherent resiliency of this member causes the central portion 21 thereof to bear upwardly against the bottom of the frame 5 and against the bottom of the carriage 15. A wedge 22 driven through the other end of the spring inside of the frame 5 holds the spring firmly in place. In this manner the carriage 15 is resiliently positioned relative to the honing element but is definitely held in sliding position and the curved portion adds to the flexibility of the spring 18. The ends of the spring at 19 limit the sliding or stroke of the carriage 15.

The carriage 15 is in the form of a guide for the blade of the instrument 23 which is to be sharpened, and the side walls 17 are inclined downwardly from the ends thereof toward the center to provide a face 24 on which the instrument 23 is to rest, as seen in the righthand side of Fig. 1. The inclination of this face 24 is such that the desired bevel will be cut on the edge of the instrument blade 23.

In order to determine the position of the blade 23 relative to the cutting face 25 of the sharpening element 7, an adjustable stop 26 is affixed by the bolts or screws 27 to the upstanding lug 28 on the side plate 17. By adjustment of these screws the stop plate 26 may be positioned to allow the instrument to slide down the inclined

face 24 the correct amount. The position of the instrument blade will vary with its thickness, the amount of sharpening to be accomplished and the pressure with which the stroke is to be applied.

In using the device the instrument blade 23 will be laid upon the two side plates 17 and against the inclined face 24 with the cutting edge of the instrument blade in the bottom of the groove and abutting against the inclined surface 29 of the stop plate 26. The plate will be adjusted so that the upper face of the instrument 23 will engage the surface 29 at about the same time that the cutting edge engages the sharpening element. The plate 26 may be of a hardened material so that it will act as a steel to prevent a feather edge on the blade. The blade will be placed with the hilt of the blade close to the carriage and with the parts in the position shown in Fig. 1, the blade will be drawn across the sharpening element while imparting a swinging motion to it so that both the carriage and the blade move to the left. In order to properly hone the blade it will now be turned over and placed on the opposite side of the carriage and the stroke will be to the right, drawing the blade across the sharpening element.

With a very little bit of practice one can become skilled in sharpening the blade with this device so that only a few strokes are necessary to place a very delicate edge upon the instrument blade.

The spring 18 yieldably supports the carriage so that the desired pressure can be applied to force the blade against the cutting element and in this way a sharpening action is assured on each stroke because the carriage will yield to any desired pressure which may be applied.

Fig. 4 shows a modified form of the carriage where only one side wall 17 and one stop plate 26 are utilized because the opposite side 31 of the carriage is cut away.

Figs. 5, 6 and 7 show another form of the device wherein the spring 18 has been dispensed with and a trackway 40 affixed to the supports 3. This trackway is substantially semicircular in form as seen in Fig. 7 and receives the bearing 41 which is arranged to slide or roll therein. The legs 3 and 4 limit the stroke of the carriage.

The base of the carriage 15 carries the fingers 43 which are spaced apart to enclose a little more than one-half of the bearing, and a bearing plate 44 carried by the carriage 15 presses against the top of the bearing. In this manner there is a point contact between the carriage and the trackway 40 tending to support the carriage for sliding movement. While one stone has been illustrated several narrower stones may be used and placed side by side with a small clearance between them.

In order to avoid friction losses between the carriage 15 and the frame 5, additional ball bearings 50 have been positioned in the ends of the carriage frame 16 as seen in Fig. 7, and these bearings reduce the friction between the carriage and the frame of the sharpener. In operation this form of the invention will be the same as Fig. 1.

Fig. 8 shows still another form wherein the trackway 52 receives the spring fingers 53 on the carriage so as to resiliently support the carriage beneath the frame 5.

The base shown may or may not be included because the larger types will probably be permanently fixed to a table, the wall or a bench.

What is claimed is:

1. A sharpener including a sharpening element, an instrument carriage, means to slidably support said carriage adjacent said element including a spring disposed beneath the sharpening element to yieldably hold said carriage for depression by the instrument being sharpened.

2. A sharpener including a sharpening element, an instrument carriage, means to slidably support said carriage adjacent said element including a spring disposed beneath the sharpening element to yieldably hold said carriage for depression by the instrument being sharpened, said spring having curved portions at its ends.

3. A sharpener including a sharpening element, an instrument carriage to slidably receive the instrument being sharpened as such instrument is drawn across the carriage, means to slidably support said carriage adjacent said element including a spring to yieldably hold said carriage for depression by the instrument being sharpened, said spring being connected beneath said element.

4. A sharpener including a sharpening element, an instrument carriage to slidably receive the instrument being sharpened as such instrument is drawn across the carriage, means to slidably support said carriage adjacent said element including a spring to yieldably hold said carriage for depression by the instrument being sharpened, said spring being connected beneath said element and spring fingers on said carriage to ride on said spring.

5. A sharpener of the character described comprising a base, a frame thereon, a sharpening element thereon, a carriage, means to slidably support said carriage by the frame for movement, means on said carriage to guide the device to be sharpened as the carriage slides along the element, said additional means including an inclined face to slidably support the device as it is drawn across the sharpening element, and an adjustable stop for the device so that it may be drawn across the carriage as the carriage travels along the element.
